UNITED STATES PATENT OFFICE.

WILLARD F. RICHARDS, OF BUFFALO, NEW YORK, ASSIGNOR TO THE GOULD COUPLER COMPANY, OF NEW YORK, N. Y.

DESIGN FOR A BASE-PLATE FOR LOCOMOTIVE-BUFFERS.

SPECIFICATION forming part of Design No. 26,515, dated January 12, 1897.

Application filed December 7, 1896. Serial No. 614,853. Term of patent 14 years.

To all whom it may concern:

Be it known that I, WILLARD F. RICHARDS, a citizen of the United States, residing at Buffalo, in the county of Erie and State of New York, have invented and produced a new and original Design for Base-Plates of Locomotive-Buffers, of which the following is a specification, reference being had to the accompanying drawings, showing a part thereof.

10 This design relates to the configuration of the base-plates or brackets of locomotive-buffers, and more particularly to a base-plate which supports the buffer and the car-coupling of a locomotive-tender.

15 In the accompanying drawings, Figure 1 is a perspective view of a base-plate embodying my design. Fig. 2 is a front view thereof. Fig. 3 is a vertical section in line 3 3, Fig. 2.

20 Like letters of reference refer to like parts in the several figures.

The leading feature of my design consists of a substantially rectangular base-plate, a pair of hollow cylindrical protuberances or sockets projecting forwardly from the upper corners of the base-plate, upright ribs or webs extending downwardly from the under side of said protuberances, a pair of upper horizontal lugs or ears arranged on the front side of the base-plate between said upright ribs and below said protuberances, and a pair of lower horizontal lugs or ears arranged directly below said upper lugs.

25 A is the substantially rectangular base-plate, which is curved at the corners, as shown, and a represents upright rows of perforations arranged near the lateral edges of the plate.

30 B are the hollow cylindrical sockets or pro-

tuberances projecting horizontally from the upper corners of the base-plate.

C are the upright ribs, which extend from 40 the under side of the protuberances B to the lower edge of the base-plate and which gradually recede from their upper toward their lower ends.

D represents the upper set of horizontal 45 perforated lugs or ears arranged, respectively, in the angles between the ribs C and the front side of the base-plate, and E represents the lower set of horizontal perforated lugs or ears arranged at the lower edge of the base-plate 50 and directly underneath the upper set of lugs D.

e represents a horizontal rib which connects the upper pair of lugs D, and e' a horizontal rib which connects the lower pair of lugs E. 55

f is a horizontal rib connecting the two cylindrical protuberances B.

g g are a pair of parallel upright ribs extending from the rib e to the rib f, and g' g' are short parallel upright ribs extending from 60 the rib f to a rim or rib g'', extending along the upper edge of the base-plate.

h is a perforated oblique lug projecting centrally from the upper edge of the base-plate.

What I claim is—

65 The design for the base-plate of a locomotive-buffer, substantially as herein shown and described.

Witness my hand this 27th day of October, 1896.

WILLARD F. RICHARDS.
